UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

DESIGN FOR A WATER COOLER

Application filed October 26, 1929. Serial No. 33,171. Term of patent 14 years.

To all whom it may concern:

Be it known that I, CHRISTIAN STEENSTRUP, a citizen of the United States, residing at Schenectady, in the county of Schenectady, State of New York, have invented a new, original, and ornamental Design for a Water Cooler, of which the following is a specification, reference being had to the accompanying drawing, forming a part thereof.

The single figure of the drawing is a perspective view of a water cooler embodying my new design.

I claim:

The ornamental design for a water cooler substantially as shown.

In witness whereof, I have hereunto set my hand this 25th day of October, 1929.

CHRISTIAN STEENSTRUP.
